Des. 178,558
Patented Aug. 14, 1956

178,558

TOY BULL DOG

William A. Uttz, Fort Worth, Tex.

Application November 28, 1955, Serial No. 39,070

Term of patent 3½ years

(Cl. D34—2)

FIG. 1.

FIG. 2.

FIG. 3.

Fig. 1 is a perspective view of a toy bull dog, showing my new design;

Fig. 2 is a side elevation thereof; and

Fig. 3 is a plan view thereof.

I claim:

The ornamental design for a toy bull dog, substantially as shown.
